LOCKING CAP FOR FUEL TANKS AND
THE LIKE

Nicholas W. Trautner, St. Paul, Minn.

Application January 18, 1943, Serial No. 472,687

1 Claim. (Cl. 70—168)

This invention relates to a fuel tank cap of the type having a lock for guarding against unauthorized removal of the cap from the filling opening or mouth of the tank.

My principal objects are to provide a novel locking cap of unusually simple, rugged construction and having a minimum number of strong, simple parts so formed that the assembly of the device is greatly facilitated and continuous, reliable operation is insured.

The invention also includes certain novel details of construction which will be more fully pointed out in the following specification and claim.

Referring to the accompanying drawings:

Figure 1 is a plan view of my improved cap in place on a filling pipe of the type commonly provided on the gasoline tanks of motor vehicles;

Fig. 2 is a central, vertical section through the same;

Figs. 3 and 4 are horizontal sections taken respectively on the lines 3—3 and 4—4 of Fig. 2;

Fig. 5 is a fragmentary, vertical section through the central portion of the cap, taken at right angles to the section shown in Fig. 2 and showing the lock cylinder;

Fig. 6 is a vertical section through the upper end portion of the filling pipe and showing an end of one of the locking arms in locked position;

Fig. 7 is a side elevation showing a modified arrangement of locking lugs and arms;

Fig. 8 is a section taken approximately on the line 8—8 of Fig. 7 and showing in dotted lines the relative positions of the filling pipe elements;

Fig. 9 is a vertical section through the upper end of the filling pipe and showing the modified arrangement of lug and locking arm, and

Fig. 10 illustrates a key for operating the lock.

In the drawings, the invention is shown in connection with a filling pipe 11 or tank mouth of the common type having an inturned flange 12 formed with oppositely disposed notches 13 to receive projecting members on the cap and a pair of oppositely disposed, inclined cam members 14 adapted to be engaged by the projecting cap members to seal and fasten the cap in sealing engagement with the pipe when the cap is turned to closed position. Each of the cam members 14 extends from one of the notches 13 to a stop shoulder 15 formed on a vertical extension 16 of the flange 12.

My improved cap has a circular body member 17 formed with an annular, pendant flange 18 adapted to extend outside of the pipe 11 and a

suitable gasket 19 for sealing engagement with the upper end of the pipe. A lock cylinder 20 is mounted centrally in the body member 17 and is provided with suitable tumblers 21 to be operated by a key, such as that illustrated in Fig. 10, which is insertible in a keyhole 22 communicating with the upper end of the cylinder 20. Projecting from the lower end of the cylinder 20 is an axial shaft 23 which may be turned by 10 the key under control of the tumblers 21, this shaft being concentric with the body member 17. At its lower end the shaft 23 is formed with a flattened head 24 which fits in a central opening in a cross bar having arms 25 projecting at 15 diametrically opposite sides of the shaft for locking engagement with the flanged upper end of the pipe 11.

An annular pendant flange 26 is integral with the cap and has oppositely disposed arcuate slots 27 to receive and guide the locking arms 25. As illustrated, the flange 26 is formed on a cap body member 28 which is rigidly fastened to the body member 17 but it will be evident that the cap body may be formed in one piece either by casting or molding a suitable plastic material or metal.

In the form of the invention shown in Figs. 1 to 6 inclusive, lugs 29 are formed on the body member 28 to fit in the notches 13 in the filling pipe flange 12 so that the cap cannot be turned when in place on the pipe. These lugs 29 are located directly above projecting ends of the arms 25 when the cap is applied to the pipe 11 and the ends of the arms are movable by the lock shaft in an arc so as to project beneath and to engage the cam members 14 at opposite sides. To move the locking arms into operative relation with the cam members 14 it is only necessary to insert the key in the hole 22 and to turn the key clockwise (Fig. 1) about 90 degrees to the locking position. This turns the shaft 23 carrying the arms 25 to the locked position indicated in dotted lines in Fig. 3. When the key is withdrawn, the tumblers 21 retain the arms 25 in locking position and thereby prevent unauthorized removal of the cap.

To facilitate the assembling of the locking mechanism in the cap, the bar constituting the arms 25 is made easily detachable from the head 24 on the lower end of the shaft 23 and the cylinder 20 is held in its central bearing in the cap body by a U-shaped detent 30 (Figs. 2, 4 and 5) which is slidable laterally in an annular groove 31 formed in the shaft 23. This detent 30 is spring pressed by a small spring 32 so that it

normally projects at one side of the shaft to engage the bottom surface of the cap body. The spring 32 is mounted in a recess in the shaft 23 and engages a stud 33 formed on the detent. To assemble the lock, it is only necessary to place the arms 25 in their guide slots 27 in the flange 26 and then to press the lock cylinder 20 downward into its bearing while retaining the detent 30 in its retracted position in the groove 31. The lock cylinder is finally seated by merely inserting the head 24 in the central opening in the arms 25 and allowing the detent 30 to spring outward into engagement with the bottom surface of the cap body, as shown in Fig. 2.

In the form of the invention shown in Figs. 7, 8 and 9, instead of providing the fixed lugs 29 which fit in the notches 13 to prevent rotation of the cap, I provide a pair of lugs 34 which are integral with the annular flange 26 and located respectively at the leading ends of the guide slots 27 with respect to the direction of rotation required to fasten the cap on the filling pipe. The normally upper surfaces of these lugs 34 are disposed to engage the bottom surfaces of the cam members 14 and to be moved to the full line position shown in Fig. 9 to retain the cap on the filling pipe, after being passed below these cam members through the notches 13. This alternate form of the invention is also characterized by an arrangement of the locking arms 25 such that they are positioned adjacent to the lugs 34 when the cap is applied to the tank opening and an arrangement of the lock cylinder and key so that the arms 25 may be moved away from the lugs 34 when the cap is to be locked in place. Thus the arms 25 may be moved to their dotted line positions indicated in Figs. 8 and 9, in which position they are locked when the key is removed, after turning the entire cap to the full line position shown. When in this locked position, the cap cannot be turned to remove the lugs 34 from engagement with the cam members 14 by reason of the fact that each of the arms 25 is locked in position to strike a vertical surface of one of the flange extensions 16 at a side of a notch 13. The lugs 34 may be made L-shaped in cross section, as shown in Fig. 9, so that a portion of each

extends above the adjacent locking arm 25 when the cap is turned to sealing position and before operating the lock.

The form of my invention shown in Figs. 7 to 9 inclusive has an advantage over the other form in that it utilizes the fixed lugs 34 to engage the cam members 14 in holding the cap in place and in drawing the gasket 19 into sealing engagement with the upper end of the pipe 11, the locking arms 25 being merely employed to prevent turning the cap to the free position on the pipe. Both of the forms of the invention have the locking arms 25 which are not only strong and rugged but are reinforced by the fixed annular flange 26 formed on the cap body and guided near their outer ends in the slots 27. There are no small, fragile parts or pivot members that can be bent or broken or that may become rusted or corroded with resulting failure of satisfactory operation. It will be further evident that the cost of assembling my improved lock is minimized by the arrangement which eliminates all screws, bolts and like fastening members and permits the lock cylinder to be fastened to the locking arms by simply pressing it into the bearing where it is held by the spring-operated detent.

Having described my invention, what I claim as new and desire to protect by Letters Patent is:

In a locking cap for a tank having a mouth and fastening members projecting within the mouth, an annular closure cap, a lock controlled shaft adapted to be turned about its vertical axis and projecting downward within the cap concentrically therewith, the improvements which comprise, a centrally located, lower end portion of said shaft formed to detachably receive and turn a locking bar, a rigid locking bar having a central bearing fitting said end portion of the shaft and affording a fixed connection therewith, opposite ends of said bar projecting to engage said fastening members within the mouth of the tank and an annular, downwardly projecting flange formed on the cap concentrically with said shaft, said flange being formed with arcuate, horizontally elongated slots to receive and guide the outer end portions of said bar.

NICHOLAS W. TRAUTNER.
